UNITED STATES PATENT OFFICE.

HENRY C. RICHARDSON, OF MERRIMAC, MASSACHUSETTS.

DESIGN FOR A LADY'S BOOT.

SPECIFICATION forming part of Design No. 21,954, dated November 1, 1892.

Application filed July 18, 1892. Serial No. 440,413. Term of patent 14 years.

To all whom it may concern:

Be it known that I, HENRY C. RICHARDSON, of Merrimac, in the county of Essex and State of Massachusetts, have invented and produced a new and original Design for Ladies' and Misses' Felt Boots, of which the following, taken in connection with the accompanying drawing, is a specification.

My design is peculiar in respect to the surface appearance of the several parts of the boot and the configuration and relative arrangement of said parts. The leg portion is somewhat longer than the foot and is crowned at the top with a band of projecting fibers resembling fur. The leg and upper portion of the foot are uniform in appearance, presenting a continuous roughened fibrous surface like some felted fabric. A smooth glossy foxing runs along the lower part of the foot, barely covering the tip of the toe, and rises

at the rear of the heel very much higher than elsewhere, the rear line of the foxing being shown as from one-third to one-half the height of the leg. The foxing does not cover the instep on the foot proper. A heel and roughened sole complete the boot. The appearance suggests a very low sandal, cut high at the heel, worn over a plain felt boot.

I claim as my invention—

The design for ladies' and misses' boots, substantially as shown and described.

In testimony whereof I have signed my name to this specification, in the presence of two subscribing witnesses, on this 5th day of July, A. D. 1892.

HENRY C. RICHARDSON.
